UNITED STATES PATENT OFFICE.

HARRY A. DOUGLAS, OF CHICAGO, ILLINOIS.

REFLECTING ELECTRIC LAMP.

1,089,750.

Specification of Letters Patent. Patented Mar. 10, 1914.

Application filed August 5, 1912. Serial No. 713,317.

To all whom it may concern:

Be it known that I, HARRY A. DOUGLAS, a citizen of the United States, residing at Chicago, in the county of Cook and State 5 of Illinois, have invented a certain new and useful Improvement in Reflecting Electric Lamps, of which the following is a full, clear, concise, and exact description, reference being had to the accompanying drawings, forming a part of this specification.

My invention relates to reflecting electric lamps and has for its object the provision of an improved construction whereby the shell that incloses the conductors for including the lamp in circuit may be employed for holding the back of the lamp and the lamp reflector in assembly.

I will explain my invention fully by reference to the accompanying drawing showing 20 the preferred embodiment thereof and which illustrates a head light partially in section and partially in side elevation.

The back element *a* of the lamp is desirably formed of sheet metal as is also the 25 reflector portion *b* whose concave surface, which is the reflecting surface, is suitably brightened for the purpose of reflecting the light which emanates from the incandescent lamp *c*. The front of the lamp is provided 30 with a hinged lid *d* for affording access to the glass front and the interior of the lamp forward of the reflector, as is well known by those familiar with these structures. The electric lamp bulb *c* has a base *c'* that 35 carries the lamp terminals *e*, the base being suitably held within a sleeve *f* that is screwed into the shell *g*. A plug *h* of insulating material has tight fit within the outer end of the shell *g* and carries two spring pressed 40 terminal contacts *i* that are in electrical connection with pins *k* carried by the plug *l* tightly held within the interior of the sleeve *f*, this structure being similar to that which forms the subject matter of another applica- 45 tion for United States Letters Patent. The conductors *m* leading from the source of current that is to supply the lamp terminates in contact pins *n* carried by a plug *o* of insulating material that is receivable within a 50 side recess in the plug *h*, the pins *n* having peripheral recesses at their upper ends to receive the spring pressed contact terminals *i*. During the absence of the plug *o* from its socket in the plug *h* a threaded nut *p* is 55 screwed into engagement with threads provided upon the rear end of the shell *g* that

projects rearwardly through the back *a*. The forward end of the shell *g* is provided with a flange *q* that is placed in front of the reflector *b*. By turning the ring *p* the reflector *b* and the back *a* are brought the proper distance apart, in which operation the flange *r* at the forward end of the reflector is pressed backwardly upon the flange *s* of the back. The shell *g* thus performs a 60 double function of housing the conductors which lead to the lamp and of holding the back *a* and reflector *b* in proper relation.

While I have herein shown and particularly described the preferred embodiment of 70 my invention, I do not wish to be limited to the precise details of construction shown, but

Having thus described my invention I claim as new and desire to secure by Letters 75 Patent the following:

1. A lamp structure including an electric lamp element; a shell housing the conductors for including the lamp element in circuit; a reflector for reflecting the light produced 80 by the lamp; a back element for holding the reflector; and a flange upon one end of the shell whereby the back element and reflector may be held together.

2. A lamp structure including an electric 85 lamp element; a shell housing the conductors for including the lamp element in circuit; a reflector for reflecting the light produced by the lamp; a back element for holding the reflector, the forward portions of the 90 back element and reflector being in engagement; and a flange upon one end of the shell whereby the back element and reflector may be held together.

3. A lamp structure including an electric 95 lamp element; a shell housing the conductors for including the lamp element in circuit; a reflector for reflecting the light produced by the lamp; a back element for housing the reflector; a flange upon one end of the shell; 100 and a threaded nut upon the other end of the shell, the back and reflecting elements being interposed between the nut and the flange, whereby the back element and reflector are held together.

4. A lamp structure including an electric lamp element; a shell housing the conductors for including the lamp element in circuit; a reflector for reflecting the light produced by the lamp; a back element for holding 110 the reflector, the forward portions of the back element and reflector being in engage-

ment; a flange upon one end of the shell; and a threaded nut upon the other end of the shell, the back and reflecting elements being interposed between the nut and the 5 flange, whereby the back element and reflector are held together.

In witness whereof, I hereunto subscribe

my name this twenty-first day of June, A. D. 1912.

HARRY A. DOUGLAS.
